UNITED STATES PATENT OFFICE.

FREDERICK A. NIEMANN, OF CHICAGO, ILLINOIS, ASSIGNOR TO NIEMANN AND COMPANY, OF CHICAGO, ILLINOIS, A CORPORATION OF ILLINOIS.

CHANGE-MAKING MACHINE.

1,253,515.

Specification of Letters Patent. Patented Jan. 15, 1918.

Application filed July 15, 1915. Serial No. 39,991.

To all whom it may concern:

Be it known that I, FREDERICK A. NIEMANN, a citizen of the United States, residing at Chicago, in the county of Cook and State of Illinois, have invented certain new and useful Improvements in Change-Making Machines, of which the following is a specification.

My invention relates to change making machines, and its object is to provide certain improvements in machines of this sort which will be hereinafter more fully described and claimed. To briefly enumerate certain of these improvements the invention 10 15 20 25 30 35 40 45 50 55 60 65 70 75 80 85 90 95 100 105 110

contemplates the construction of the coin containing and ejecting means whereby the operation of ejecting the coins may be very rapidly performed without danger of inaccuracies. The invention provides further a construction whereby the machine, by certain simple substitutions of parts, can be adapted for several different uses, for example, for filling pay roll envelops, for delivering change direct to a customer or for delivering the change to the operator in the usual manner.

A further object of the invention is to provide a change making machine which will be very simple in its construction, economical of manufacture (the machine being made of a relatively small number of stampings and castings) and one which, because of features of construction to be hereinafter described and claimed, will be positive in its action and will not be likely to get out of order even when somewhat roughly used.

Other advantageous features of construction will appear from the following description.

The invention is illustrated in certain preferred embodiments, in the accompanying drawings wherein—

Figure 1 is a view, in perspective, of a change making machine constructed in accordance with the principles of my invention, the machine in this case being shown as provided with a chute adapted particularly for delivery of change directly to a customer.

Fig. 2 is a vertical sectional view of the machine shown in Fig. 1.

Figs. 3 and 4 are sectional views taken on lines 3—3 and 4—4 respectively, of Fig. 2.

Fig. 5 is a view, in perspective, of one unit of the ejecting mechanism.

Fig. 6 is a similar view of one of the coin ejecting slides.

Fig. 7 is a view, in perspective, of the inner or coin receiving chute.

Fig. 8 is a view similar to Fig. 1 showing the machine as provided with a coin delivery chute adapted particularly for filling pay envelops, or the like.

Fig. 9 is a view similar to Fig. 2 illustrating the machine as provided with a coin chute which delivers the coins through the front plate under the operating keys so that they may be conveniently collected by the person operating the machine.

Fig. 10 is a view, in perspective, of a coin ejecting chute provided with means for preventing the coin from being only partly ejected from the coin pocket, and

Fig. 11 is a similar view of the coin chute employed in the machine illustrated in Fig. 9.

Like characters of reference designate like parts in the several figures of the drawings.

Referring first to Figs. 1 to 7 inclusive, the casing of the machine is shown as consisting of a lower casing member 25 preferably closed in front by a front plate 26 and an upper casing member 27. The front plate 26 is removably secured to the lower member 25 by screws 28. The upper member 27 is secured to the lower member 25 by screws 29. The lower member is preferably formed with pockets 30 for rubber pads 31. The lower casing member is formed with a horizontal web or base plate 32 which does not extend to the back edge of the casing. The upper casing member is formed with webs 33 providing coin pockets 34 adapted to receive stacks of coins. Above the coin pockets the web 35 of the upper casing member is slanted backwardly and recessed so as to form inclined chutes 36 which deliver the coins into the coin pockets. The front portion 37 of the upper casing member forms a cover for the base plate 32 and coin ejecting slides 38 which are arranged thereon.

The coin ejecting mechanism consists of ejecting units, one operating in connection with each of the coin pockets, which are just alike except in the one respect to be hereinafter noted. The unit for ejecting fifty cent pieces is shown in Figs. 2 and 5 and it will be sufficient to describe this single unit. 39 is a lever preferably stamped 110

out of sheet metal and provided with a finger piece or key 40. The lever is formed with an angular projection providing a member or plate 41 which is substantially parallel with the body of the lever. The lever is mounted on a rod 42 which is fitted in openings in the end walls 43, 44 of the lower casing member. The rod passes through the spacing plate 41 as well as through the main portion of the lever. In this manner the lever has a double bearing on the rod which prevents it from wobbling even though it is made of relatively thin metal. The lever 39 is in the form of a bell crank having a short arm 45 which has a rotative and slidable engagement with a lever 46 fulcrumed on a rod 47 which latter is mounted in the casing member 25 below rod 42. The lever 46 is also preferably formed with an angular projection 48 similar to the angular projection 41 of the lever 39 and serving the same purpose. The lever 46 extends around and above the lever 39 and terminates in a rounded end 49 which projects through a slot 50 in the coin ejecting slide 38. The engagement between the lever 39 and the lever 46 is provided by slitting the upper edge of the lever 46 and bending back the metal so as to form a pair of lugs 51 between which the rounded end of the short arm 45 of lever 39 extends. Preferably the distance from the axis of rod 47 to the point of contact between the levers is less than the distance from said point to the axis of rod 42. In other words the short arm of lever 46 is shorter than the short arm of lever 45 as a result of which the coin ejecting slide 38 is given a movement which is sharper and quicker than the movement of key 40. This is enhanced preferably by making the long arm of lever 46 considerably longer than the short arm thereof. The rounded end of the short arm 45 of the manipulating lever 39 can slide as well as rotate between the lugs 51, this being necessary in view of the difference in radius between the engaging arms.

The coin ejecting slide 38 is formed with down turned flanges 52 which lie in slots 53 formed in the base plate 32. The base plate is also formed with a slot 54 between slots 53 through which the end of lever 46 extends. The lever 46 is formed with a projection 55 connected to a helical spring 56. The other end of the spring is anchored to a rod 57 which is bound against a rib 58 on the under side of the base plate by means of cotter pins 59.

The several units constructed as above described are arranged side by side with the spacing projection of each lever bearing against the body portion of the adjacent lever. The end levers are preferably held in proper position by spacing sleeves 60, 61. 65 In order that twenty cents in change may

be ejected by a single operation I have provided the machine with two ten cent coin pockets 34^a, 34^b. The coin ejecting slide 38^a, forming a part of a coin ejecting unit, the key 40^a of which is marked "10", 70 is moved, when key 40^a is depressed independently of the mechanism that ejects coins from the other ten cent pocket 34^b. The coin ejecting slide 38^b of the latter unit, the key of which, 40^b, is marked "20", is formed 75 with a laterally projecting lug 62 which engages a lug 63 on the slide 34^a. When the twenty cent key 40^b is depressed slide 38^b ejects a coin from pocket 34^b, and at the same time slide 38^a is moved to eject a coin 80 from the pocket 34^a.

The manipulating levers 39 extend through slots 64 in the front plate 26. The length of these slots is such that the levers 39 cannot be depressed far enough to throw the 85 corresponding slide engaging levers into such position that the latter will not be automatically returned by springs 56 to their normal positions when the pressure of the fingers is taken from the keys.

The coins ejected from the coin pockets are pushed over the rear marginal edge of base plate 32 and fall into an inclined receiving chute 65. This chute is made of sheet metal, preferably, and is removably 95 arranged within the lower casing member 25 with its delivery end communicating with an opening 66 in the end wall 44 of the casing. In fact, the chute requires no attachment to the casing. It has enough 100 spring to hold it in the proper position. To the outside of the casing is attached a coin delivery chute 67 which is preferably formed with a bend toward the side of the machine opposite to the side on which the keys are 105 arranged. The end wall 44 of the casing is formed with slots 68 and the chute with hooks 69 which enter the slots. The engagement is preferably made more firm by a screw 70 which extends through a lug 71 110 on the chute and into the end wall 44. The receiving chute 65 is preferably formed with a lip 72 which overlaps the delivery chute a trifle. The delivery chute is preferably provided with a cross piece 73 which stands far 115 enough above the bottom of the chute so that it intercepts any rolling coin and causes the same to drop on its side and in that manner slide the rest of the way through the chute.

The construction of the ejecting mechanism is such that the coin is ejected by a sharp, quick movement of the ejecting slide. If the machine be properly operated the coins will be ejected without fail. By a 125 careless operation, that is, if the key is not depressed far enough, it may happen that a coin is partially removed from under the stack but is removed far enough so that the coins above are turned into an oblique posi- 130

tion preventing the slide when actuated again from reaching the partially ejected coin. In order to straighten the stack the upper casing member is formed at the 5 pockets with a plurality of notches 74 and the keys 38 are similarly formed on their inner ends with notches 75. This permits a pencil or other thin instrument to be inserted under the forward edge of the stack 10 so as to raise it sufficiently to allow the slide to be brought against the lowermost coin or partially ejected coin.

In Fig. 8 I have shown a machine, in all other respects like the machine just described, which is provided with a discharge chute 67^a intended particularly for delivering change to pay envelops, or the like. The chute is shown as formed with hooks 69^a adapted to engage the end of the casing of 20 the machine through the slots 68, and with a screw 70^a for binding it to the casing. The intention is to have the machine furnished with two chutes of the sort above described either one of which can be used as required.

25 In Fig. 9 I have shown the same machine with certain parts interchanged so that the coins will be delivered to the side of the machine at which the keys are located so that the change may be handled by the operator.

30 This is the usual way in which the change ejected by change making machines is handled and while I consider that the immediate delivery of the change to the customer, or into the pay envelop as provided 35 by the constructions previously described, will be of considerable advantage, it may happen that under some circumstances it will be more desirable for the person who operates the machine to collect the coins 40 ejected by the machine and give them to the customer or make such other disposition of the same as the circumstance calls for. In order to modify the machine in such manner 45 that the ejected coins can be conveniently handled by the person who operates the machine, the front plate 26 of the machine as previously described is removed, together with the receiving chute 65, and for the latter a chute 76 (Fig. 11) is substituted.

50 The chute 76 is provided with a slotted lug 77 adapted for engagement with the screw 29 which holds together the rear edges of the upper and lower casing members 27, 26. At the forward end of the chute are slotted 55 brackets 78 which hook over the ends of the rod 47 on which the slide engaging levers 46 are fulcrumed. A front plate 79 is substituted for the front plate 26. The coins ejected from the stacks fall into the chute 60 76 and are delivered to the front side of the machine, that is, to the side at which the operating keys are located.

I have shown in connection with the machine of Fig. 9 a slight modification in the 65 construction of the coin ejecting slides

which, however, could be used as well in connection with the machines previously described. The slide 38^c (Fig. 10) has attached to the inner end thereof a bar 80 formed at its extremity with an upstanding lug 81. The bar projects from the slide a distance equal, substantially, to the diameter of the coins of the stack operated upon. The bar moves in the slot 54 of the base plate formed for the accommodation of the end of the slide engaging lever 46. It lies, normally, directly under the stack of coins. If the manipulated lever 39 is given its full stroke so that the coin operated upon is completely freed from the stack of coins above it, the coin will readily fall from the bar 80 into the receiving chute. On the other hand, if the manipulated lever is not depressed sufficiently the lug 81 on the bar 80 engages the coin and returns the same to its normal 85 position under the stack when the operating levers are returned to their positions of rest by the spring 56. By this expedient it is impossible, if a coin is partially ejected, through careless operation, for the coins 90 above it to take an oblique position blocking the further operation of the ejecting mechanism.

Résumé of operation.—With the coin pockets filled with coins of the proper denomination, change is made by depressing the manipulated levers corresponding to the different coin stacks. The throw of the manipulated levers is relatively short. The movement of the ejecting slides 38 is, nevertheless, very rapid because of the compound lever arrangements by which the slides are operated. The engagements between the levers 39 and the corresponding slide engaging levers 46, and between the latter and the slides, are very free so that the apparatus responds to a light touch and the possibility of the parts sticking or clogging is eliminated. The coins are ejected directly into the receiving chute. The action is, therefore, simple and positive. There is no danger if the machine is properly operated that the proper coin will not be ejected at every depression of the key. The machine can be run at a high rate of speed which is particularly important perhaps when it is used for placing change in pay roll envelops. When the machine is used in this connection it is preferably provided with the delivery chute 67^a (Fig. 8). If the machine is to be used for delivering change directly to a customer, in a store or restaurant for example, the chute 67^a is removed by loosening screw 78 and unhooking the chute from slots 68 and the chute 67 is put in its place. This chute delivers the coin toward the side of the machine away from the operator, that is, the side toward the customer, so that the operator does not have to handle the coins at all.

If through careless operation a coin should not be fully ejected, with the result that the coins in the stack above take an oblique position blocking the further operation of the ejecting apparatus, this may be remedied by placing a pencil through the notch 74 in the casing and the corresponding notch 75 in the end of the slide and raising the forward edge of the stack sufficiently to allow the slide to pass and come into contact with the partially ejected coin. If the slides are constructed as shown in Fig. 10, the tilting of the stack cannot occur under such circumstances, but the provision of the slides with the projections 80 makes the ejecting action a trifle slower so that, where the highest rate of operation is desired, I prefer not to employ this feature. When it is desired to have the operator handle the change the inner or receiving chute 66 is removed, together with the front plate 26, and a chute 76 (Fig. 9) which delivers the coins to the front of the machine, under the front plate 79, is put in place of the other chute.

While I have described my invention in certain preferred embodiments, it will be understood that further modifications might be made without departure from the principles of the invention. Therefore I do not wish to be understood as limiting the invention to the particulars described and shown except so far as certain of the claims are specific thereon.

I claim:

1. In a change making machine, the combination of a coin ejecting slide formed with a slot, a lever, one end of which is rounded and projects into said slot, a manipulated lever, and means providing a connection whereby lost motion is prevented between

said levers comprising a rounded end on one of said levers and a socket to receive the same formed on the other lever.

2. In a change making machine, the combination of a coin ejecting slide formed with a slot, a slide engaging lever one end of which is rounded and projects into said slot, a manipulated lever, and means providing a connection between said levers comprising a rounded end on one of said levers and a socket to receive the same formed on the other lever in which said rounded end may have movement both of rotation and translation; the arm of the slide engaging lever thus connected with the other lever being longer than the arm to which it is connected.

3. In a change making machine, the combination of a coin ejecting slide formed with a slot, a lever having a longer arm terminating in a rounded end engaging said slide through the slot, and a short arm formed with a laterally extending pair of lugs providing a socket, a lever fulcrumed above said first named lever having an arm terminating in a rounded element the periphery of which projects between and bears against the lugs of the first named lever, and an arm provided with a finger key.

4. In a change making machine, the combination of a casing provided with a coin pocket, an ejecting slide provided with a hooked extension on its ejecting end which is narrow relative to the diameter of the coin operated upon and in length is substantially the same as the diameter of said coin.

FREDERICK A. NIEMANN.
